UNITED STATES PATENT OFFICE.

CLARENCE W. COLEMAN, OF CHICAGO, ILLINOIS, ASSIGNOR TO THE HALL SIGNAL COMPANY, A CORPORATION OF MAINE.

SIGNAL-OPERATING APPARATUS.

SPECIFICATION forming part of Letters Patent No. 693,109, dated February 11, 1902.

Application filed October 24, 1900. Serial No. 34,140. (No model.)

To all whom it may concern:

Be it known that I, CLARENCE W. COLEMAN, a citizen of the United States, and a resident of Chicago, county of Cook, and State of Illinois, have invented a new and useful Improvement in Signal-Operating Apparatus, of which the following is a specification.

My invention relates to signals, and especially to devices for operating signals.

It has for its object to provide a signal-operating apparatus which will operate one or two signals, which will operate two signals from a common motor or source of power, and will operate them independently of each other.

It also has for its object to simplify and improve signal-operating apparatus and to make it certain in operation.

It consists of the novel devices and combinations herein set forth.

Although not limited to such devices, my improvement is of particular value in railway automatic signaling apparatus, and in the accompanying drawings, forming part of this specification, and in which similar reference characters in the different figures represent corresponding parts, I have shown the preferred form of my improved devices as connected with automatic railway-signals and with the usual home and distant signals commonly employed, although it will be understood that my devices may be used with other than home and distant signals.

Referring to the specific form or embodiment of my invention shown in the drawings, Figure 1 is a view of a pair of home and distant signals mounted upon a standard and showing the method of connection with my improved signal-operating devices. Fig. 2 is a side and detail view of certain parts of my improved signal-operating devices. Fig. 3 is a plan of the said parts. Fig. 4 is a side view of the same parts and some of their connections viewed from the opposite side from that of Fig. 2. Fig. 5 is a detail of parts of the signal-operating apparatus. Fig. 6 is a front view of the driving parts of my improved apparatus, and Fig. 7 is a diagrammatic view showing one system of circuits by means of which my improved devices can

be controlled automatically by a train on the track.

Referring now to the specific form or embodiment shown in the drawings, 1 represents a home signal, and 2 a distant signal, arranged in a pair and mounted in the usual way upon a standard 3. As shown, the signals are normally held at "safety" each through an actuating-rod 4, moved as will hereinafter be described. The signals are counterweighted at 5 in the usual manner, so that when left free to move they will move to "danger." Two signals are operated from a common motor 6. Power is transmitted from the motor through connections between it and the two signals, so as to operate the signals independently of each other. To accomplish this, I provide in the connections between the motor and the signals a common operating part, which in the form shown in the drawings consists of gear-wheel 7, and between this and one of the signals—as shown, the home signal—I arrange two latches adapted to be engaged with or be disconnected from each other to connect the motor with or disconnect it from the said home signal. One of these latches is mounted on the gear-wheel 7, and consists of swinging latch 8, pivoted at 9 to the wheel. The other latch consists in the form shown of the armature-lever 10 of magnet 11. (Shown in Fig. 2.) Armature-lever 10 is pivoted at 12 to a revolving arm 13, loosely mounted upon shaft 14, the same shaft as that upon which gear 7 is mounted. Arm 13 carries with it magnet 11 and its connections, and at its left end, as viewed in Fig. 2, is connected with a rod 15, which is connected by a lever 16, back of the one shown in Fig. 1, with operating-rod 4 of home signal 1. The pivotal connections between rod 15 and lever 13 are made by means of a link 15^a. (Shown in dotted lines in Figs. 2, 4, and 6.) Operating-rod 4 of distant signal 2 is similarly operated by a rod 15 and an additional lever. (Shown as 16 in Fig. 1.) Latch 10 is provided at its right end, viewed as shown in Fig. 2, with a toe or projection 17, which is adapted to engage with the square foot of swinging latch 8, as shown in Fig. 2. A spring 18 presses latch 8 toward latch 10, causing a yielding engagement with toe 17 of 100

the latch. Gear 7 is driven from the motor through shaft 19, pinion 20, gear 21, shaft 22, and gear 23 of the same shaft. It is always driven in the same direction and causes gear 7 to rotate in the direction of the arrow shown in Figs. 2 and 4. Latches 10 and 8 are held in operative engagement with each other whenever magnet 11 is energized. In this position of the parts if gear 7 be driven by motor 6 revolving arm 13 will be rotated on its axis and the home signal 1 will be moved to "safety." In order to insure that swinging latch 8 will be held in engagement with latch 10, I preferably mount upon one side of the frame-work a cam-surface 24, which will positively hold latch 8 against latch 10 until signal 1 has been moved to safety position. By the time this has been done toe 17 has come opposite and has been caught by the teeth of rack 25. This rack acts as a catch for holding the latch 10, and with it the signal, in its set position. Rack 25 is pressed by spring 26, so as to engage with toe 17. In order to positively withdraw latch 8 from engagement with toe 17 of latch 10, I preferably mount upon the framework of the machine a cam-surface 27, which is arranged to lie in the path of a pin 28 projecting from the side of latch 8. As pin 28 engages cam-surface 27 latch 8 is positively withdrawn from engagement with the toe of latch 10. By the movement of the parts thus described home signal 1 has been moved to its safety position and is caught and held there, and at the same time the engagement between it and gear 7 is broken, so that the latter is free to continue its rotation. It will be understood that this position of home signal 1 takes place only when magnet 11 is energized and only when the motor itself is energized. As long as magnet 11 remains deenergized the toe 17 of catch 10 simply moves out of the way of catch 8 should gear 7 be rotating. When it is desired to release home signal 1 from its safety position, as held there by catch 25, magnet 11 is deenergized, whereupon armature 10 is released and toe 17 slips off from the teeth of rack 25, arm 13 and all it carries returns to its normal position, and signal 1 returns to danger position, all through action of counter-weight 5. After home signal 1 has been moved to its safety position, as above described, danger-signal 2 can be moved to its safety position by the further rotation of gear 7 by the following-described means: Between gear 7 and distant signal 2 I also preferably place a latch for connecting them together or for disconnecting them. In the form shown it consists of a similar armature-lever 29, pivoted at 30 upon a revolving arm 31, loosely mounted upon shaft 14 and operated by a magnet 32, all as shown in Fig. 4. It also has a toe 33, which projects into the path of a projection 34 from one side of gear-wheel 7, as shown in Fig. 4. As gear-wheel 7 rotates projection 34 strikes toe 33, and if magnet 32 is deenergized simply idly pushes it out of the

way without moving arm 31. If magnet 32, however, is energized, latch 29 is operatively held and the rotation of gear 7 rotates arm 31, which carries with it magnet 32 and rod 15. Rod 15 is connected with rod 4 by means of lever 16, pivoted in the casing. This additional lever is inserted in order to give the proper direction of motion to rod 4 to move 75 distant signal 2 to "safety." When latch 29 is released through the devitalizing of magnet 32, distant signal 2 returns to "danger."

In practice I prefer to place two latches 8 on gear-wheel 7, arranged diametrically opposite each other, and also to place on the other face of gear-wheel 7 two projections 34, also arranged diametrically opposite each other and so placed on the periphery of the gear-wheel that each projection 34 is ninety degrees away from each latch 8. In this way the gear 7 when operatively connected with the signals will first move the home signal to "safety," where it will be caught and held by rack 25, and then gear 7 will begin to move 75 distant signal 2 to "safety," provided, of course, the proper magnets are energized. A half-turn of gear 7 will thus move both signals to their set position—as here shown, the safety position. When gear 7 has thus made 95 a half-revolution, I prefer to use means for automatically deenergizing the motor, and thus stopping the movement of gear 7 at this point. As such means are well known they are not here shown and described, except diagrammatically. The stoppage of wheel 7 causes projection 34 to hold toe 33 in the position to which it has been moved, thus holding distant signal 2 in its set or safety position, and this continues until magnet 32 is deenergized, and toe 33 consequently released from projection 34. When the motor and the proper magnet or magnets are again energized, gear 7 is again rotated in the same direction another half-revolution, and so on. 100 The motor thus drives the gear 7 always in the same direction. A pawl 35, engaging with ratchet-wheel 36 on shaft 22, prevents backward rotation of these parts.

Any suitable means may be employed for 115 controlling the latches; but I prefer to use automatic means and preferably magnets controlled by a train upon the track. Any suitable system of circuits may be employed for this purpose. In Fig. 7 I show a diagrammatic view of one system of circuits which I have found useful in connection with my improved devices, and I will now proceed to describe the system as there shown.

The track is divided into blocks 37 38 39 40 125 in the usual manner, each insulated from adjoining blocks and provided, as shown, with batteries 41, 42, and 43. Each track-circuit is provided with a relay. As shown, they are 44, 45, and 46. Each of these relays controls 130 a magnet 11 through circuit-controllers 47, 48, and 49, respectively. Each magnet 11 controls a latch 10 for home signal 1, as has been already described. This armature is

shown in the diagram of Fig. 7. With no train on the track the track-circuits are normally closed, circuit-controllers 47, 48, and 49 are held in their closed position, and relays 5 11 are energized, thus holding home signal 1 normally at "safety." The circuit through magnet 11—say of block 39—is as follows: battery 50, wire 51, circuit-controller 48, wire 52, magnet 11, wire 53, main-line wire 54, back to battery. When a train enters upon a block—for example, block 39—it deenergizes magnet 45 and with it magnet 11, sending the home signal 1 to "danger." Each home signal 1 mechanically and automatically controls three 15 different sets of contact-points. As shown in Fig. 7, these are shown as connected with operating-rod 4 of home signal 1, and consist of contact-points 55 to enable the home signal in its movement to control the distant 20 signal 2 of the same pair, contact-points 56 to enable it to control the distant signal of the pair of signals in the rear of the home signal in question, and, lastly, contact-points 57 to control the motor-circuit. When the home 25 signal stands at "safety," contact-points 55 56 are closed and contact-points 57 are open. As the home signal goes to "danger" contact-points 55 and 56 are broken, thus sending to "danger" or keeping at "danger" the distant 30 signal of the same pair and the distant signal in the rear, and contact-points 57 are closed, closing that break in the motor-circuit. Each of these circuits will now be separately described. The circuit through contact 55 is 35 as follows: from battery 50 of block 40 to wire 58, circuit-controller 49, wires 52 59, contact-points 56 of home signal 1 of block 40, wire 60, contact-points 55 of home signal 1 of block 39, wire 61, magnet 32 of distant signal 40 2 of block 39, wires 62 63, and line-wire 54 back to battery. The break at contact-points 55 made by home signal 1 of block 39 going to "danger" thus insures its corresponding distant signal 2 going to "danger" or staying 45 at "danger" if already there. The circuit through contact-points 56 of home signal 1 of block 39 is as follows: battery 50 of block 39, wire 51, circuit-controller 48, wires 52 59, contact-points 56, wire 60, contact-points 55 of home signal 1 of block 38, wire 61, magnet 32 of distant signal 2 of block 38, wires 62 63 to line-wire 54, to battery. This insures that the distant signal 2 in the rear of the home signal in question, or, in other 55 words, the distant signal 2 of block 38 will go to "danger," or if already at "danger" will stay at "danger" when home signal 1 of block 39 goes to "danger." The motor-circuit through contacts 57 is as follows: battery 64 of block 39, wire 65, motor 6, wire 66, contact-points 57, wire 67, armature 68 of magnet 11 of block 39, wire 69, back to battery. When home signal 1 moves to "danger," the break at 57 in this circuit is closed. 60 As long as the train remains on block 39, however, the motor will not be energized, owing to the break in magnet 11 at controller 48.

As soon as the train moves off block 39 this break is closed, the motor is energized, and the home signal 1 of block 39 is hauled to 70 its safety position, thus breaking motor-circuit at 57 and closing the contacts 55 and 56, permitting distant signal 2 in the rear to go to "safety." The contacts at 71 and 57 are not shown in detail in the diagram Fig. 7, 75 their presence only being indicated in that diagram. These contacts are made in the usual manner, and are of course arranged so that they are not broken as the signals move to "safety" until the safety position is 80 reached. Such construction is so well known that it is not shown in detail in the drawings. As long as train remains on block 40, however, distant signal 2 of block 39 cannot go to "safety" because of the break at contact- 85 points 56 made by home signal 1 of block 40 being at "danger."

When the train moves off from the block 40, these contact-points are closed and the distant signal 2 of block 39 can then go to 90 "safety." The motor 6 of this block is energized for this purpose through a branch of the motor-circuit from battery 64, which runs from wire 66 through wire 70, contact-points 71, secured to operating-rod 4 of distant signal 95 2 in question, wire 72, circuit-controller 73 of magnet 32 of the said distant signal, wire 74, wire 69, to battery. Contact-points 71 are normally broken when danger - signal 2 is at "safety" and are closed when it 100 goes to "danger." By means of my improved devices both signals form a pair and can be operated independently of each other and by a single motor. My improved devices are simple in construction and efficient and cer- 105 tain in operation. By means of them the driving parts can always be driven in the same direction.

In operating a single signal with my device the swinging latch 8, magnet 11, arm 13, and 110 connections will not be used, but those parts which have been above described as being used to operate the distant signal will in such case be employed. The signal will be held in the clear position by pawl 35 engaging 115 ratchet-wheel 36 on shaft 22, preventing gear 7 from rotating backward. Upon the magnets becoming deenergized the signal will go to "danger," and when the magnets and motor are again energized the next lug on 120 gear-wheel 7 will carry the signal to clear position, and so on. Any suitable number of lugs may be employed upon the side of gear-wheel 7 for this purpose, thus allowing one-fourth or one-fifth or other fractional 125 turn of gear 7 to put the signal in clear position.

In the devices shown and described herein the set position into which signals are moved by the motor is shown as the safety position. 13: Such set position could, of course, be the danger position, if it be so desired. Many other modifications in or departures from the devices shown in the drawings could also be

made without departing from my invention, the essentials of which are set forth in the claims at the end of the specification.

My invention is shown in connection with 5 signals, although it is not limited to use with signals, but may be used with other objects which are to be moved into a set position. It will thus be understood that wherever the term "signals" is used in the claims or in the 10 statement of invention herein it is used in a sense broad enough to include any other or similar objects which are to be moved into set position and to which my invention is applicable.

15 What I claim as new, and desire to secure by Letters Patent, is—

1. The combination in a signaling device of two signals, a motor for moving said signals successively into set position, connections between the motor and each of said signals, one of said sets of connections containing two latches adapted to engage with or be disconnected from each other to connect the motor with or disconnect it from one of its signals, 25 one latch adapted to be controlled by a train upon the track, means for automatically causing the two latches to be disconnected from each other when their signal has been moved into set position to permit the motor to move 30 the other signal thereafter into its set position, and a catch for engaging the first latch to hold its signal in set position, whereby one signal may be operated independently of the other by the same motor.

35 2. The combination in a signaling device of two signals, a motor for moving said signals successively into set position, connections between the motor and each of said signals, one of said sets of connections containing two latches adapted to engage with or be disconnected from each other to connect the motor with or disconnect it from one of its signals, one latch adapted to be controlled by a train upon the track and the other latch adapted 45 to be held against the first-mentioned latch when the signal is to be moved by the motor into set position and to be withdrawn therefrom at the close of such movement, means for automatically causing the two latches to 50 be disconnected from each other when their signal has been moved into set position to permit the motor to move the other signal thereafter into its set position, and a catch for engaging the first latch to hold its signal in set position, whereby one signal may be operated independently of the other by the same motor.

55 3. The combination in a signaling device of two signals, a motor for moving said signals successively into set position, connections between the motor and each of said signals, one of said sets of connections containing two latches adapted to engage with or be disconnected from each other to connect the motor with or to disconnect it from one of its signals, one latch adapted to be controlled by a train upon the track, means for positively 60 holding the other latch against the first-men-

tioned latch when the signal is to be moved by the motor into set position, means for positively withdrawing it from such engagement 70 at the close of such movement, and a catch for engaging the first latch to hold its signal in set position, whereby one signal may be operated independently of the other by the same motor.

75 4. The combination in a signaling device of two signals, a motor for moving said signals successively into set position, connections between the motor and each of said signals, one of said sets of connections containing two latches adapted to engage with or be disconnected from each other to connect the motor with or disconnect it from one of its signals, one latch adapted to be controlled by a train upon the track, means for positively holding the other latch against the first-mentioned latch when the signal is to be moved by the motor into set position, means for automatically causing the two latches to be disconnected from each other when their signal 90 has been moved into set position to permit the motor to move the other signal thereafter into its set position, and a catch for engaging the first latch to hold its signal in set position, whereby one signal may be operated independently of the other by the same motor.

95 5. The combination in a signaling device of two signals, a motor for moving said signals successively into set position, connections between the motor and each of said signals, one of said sets of connections containing two latches adapted to engage with or be disconnected from each other to connect the motor with or disconnect it from one of its signals, one latch adapted to be controlled by a train upon the track and the other latch adapted 100 to be held against the first-mentioned latch when the signal is to be moved by the motor into set position, means for positively withdrawing it from such engagement at the close 105 of said movement, and a catch for engaging the first latch to hold its signal in set position, whereby one signal may be operated independently of the other by the same motor.

110 6. The combination in a signaling device of two signals, a motor for moving said signals successively into set position, connections between the motor and each of said signals, one of said sets of connections containing two latches adapted to engage with or be disconnected from each other to connect the motor with or disconnect it from one of its signals, one latch adapted to be held against the other latch when the signal is to be moved by the motor into set position and to be withdrawn 115 therefrom at the close of such movement, a catch for engaging the other latch to hold its signal in set position, and means controlled by the train on the track to hold the latter latch in engagement with the other latch and 120 with the catch or to disconnect it therefrom, whereby one signal may be operated independently of the other by the same motor.

125 7. The combination in a signaling device of

- two signals, a motor for moving said signals successively into set position, connections between the motor and each of said signals, one of said sets of connections containing two latches adapted to engage with or be disconnected from each other to connect the motor with or disconnect it from one of its signals, means for automatically causing the two latches to be disconnected from each other when their signal has been moved into set position to permit the motor to move the other signal thereafter into its set position, a catch for engaging one latch to hold its signal in set position, means controlled by the train on the track to release said latch from the catch to permit said signal to return to its normal position, whereby one signal may be operated independently of the other by the same motor.
8. The combination in a signaling device of two signals, a motor for moving said signals into set position, connections between the motor and each of said signals, said connections having a common operating part, driven by the motor, a latch mounted thereon, another latch adapted to be connected with one of the signals and to engage with the latch on the common operating part, means controlled by the train on the track for energizing the motor and for operatively connecting the said latches together when the signal is to be moved into set position, a catch for engaging the latch connected with the signal to hold the latter in set position, means controlled by a train on the track to release the latch from the catch, a latch adapted to be operatively connected with the other signal and when thus connected controlled by a train on the track for operatively connecting the latch with the signal, whereby one signal may be operated independently of the other by the same motor.
9. The combination in a signaling device of two signals, a motor for moving said signals into set position, connections between the motor and each of said signals, said connections having a common operating part, driven by the motor, a latch mounted thereon, another latch adapted to be connected with one of the signals and to engage with the latch on the common operating part, means for energizing the motor and for operatively connecting the said latches together when the signal is to be moved into set position, means for automatically causing the two latches to be disconnected from each other when their signal has been moved into set position to permit the motor to move the other signal thereafter into its set position, a catch for engaging the latch connected with the signal to hold the latter in set position, means for releasing the latch from the catch, a latch adapted to be operatively connected with the other signal, and when thus connected adapted to be engaged and moved by the common operating part to move its signal to set position, and means controlled by a train on the track to release the latch from the catch, a latch adapted to be operatively connected with the other signal and when thus connected adapted to be engaged and moved by the common operating part to move its signal to set position, and means controlled by a train on the track for operatively connecting the latch with the signal, whereby one signal may be operated independently of the other by the same motor.
10. The combination in a signaling device of two signals, a motor for moving said signals into set position, connections between the motor and each of said signals, said connections having a common operating part, driven by the motor, a latch mounted thereon, another latch adapted to be connected with one of the signals and to engage with the latch on the common operating part, means controlled by the train on the track for energizing the motor and for operatively connecting the said latches together when the signal is to be moved into set position, means for positively holding the latch mounted on the common operating part in engagement with the other latch, while the signal is being moved into set position, means for positively withdrawing the latch from engagement with the signal-latch at the close of such movement, a catch for engaging the latch connected with the signal to hold the latter in set position, means controlled by a train on the track to release the latch from the catch, a latch adapted to be operatively connected with the other signal and when thus connected adapted to be engaged and moved by the common operating part to move its signal to set position, and means controlled by a train on the track for operatively connecting the latch with the signal, whereby one signal may be operated independently of the other by the same motor.
11. The combination in a signaling device of a signal, a motor for moving the signal into set position, connections between the motor and the signal containing two latches adapted to engage with or be disconnected from each other to connect the motor with or disconnect it from the signal, means for controlling one latch adapted to cause said latch to operatively engage with the other latch when the signal is to be moved into set position and not to operatively engage with it when the signal is not to be set, and the other latch adapted to be held against the first-mentioned latch when the signal is to be moved by the motor into set position and to be withdrawn therefrom at the close of such movement, whereby the signal and motor will be operatively connected only while the signal is being moved into set position.
12. The combination in a signaling device of a signal, a motor for moving the signal into set position, connections between the motor and the signal containing two latches adapted to engage with or be disconnected from each other to connect the motor with or disconnect it from the signal, means for controlling one latch adapted to be automatically actuated by a track-circuit to cause said latch to operatively engage with the other latch when the signal is to be moved into set position and not to operatively engage with it when the signal is not to be set, and the other latch

operatively connecting the latch with the signal, whereby one signal may be operated independently of the other by the same motor. 70

10. The combination in a signaling device of two signals, a motor for moving said signals into set position, connections between the motor and each of said signals, said connections having a common operating part, 75 driven by the motor, a latch mounted thereon, another latch adapted to be connected with one of the signals and to engage with the latch on the common operating part, means controlled by the train on the track for energizing the motor and for operatively connecting the said latches together when the signal is to be moved into set position, means for positively holding the latch mounted on the common operating part in engagement with 80 the other latch, while the signal is being moved into set position, means for positively withdrawing the latch from engagement with the signal-latch at the close of such movement, a catch for engaging the latch connected with the signal to hold the latter in set position, means controlled by a train on the track to release the latch from the catch, a latch adapted to be operatively connected with the other signal and when thus connected 85 adapted to be engaged and moved by the common operating part to move its signal to set position, and means controlled by a train on the track for operatively connecting the latch with the signal, whereby one signal may be operated independently of the other by the same motor.

11. The combination in a signaling device of a signal, a motor for moving the signal into set position, connections between the motor and the signal containing two latches adapted to engage with or be disconnected from each other to connect the motor with or disconnect it from the signal, means for controlling one latch adapted to cause said latch to operatively engage with the other latch when the signal is to be moved into set position and not to operatively engage with it when the signal is not to be set, and the other latch adapted to be held against the first-mentioned 115 latch when the signal is to be moved by the motor into set position and to be withdrawn therefrom at the close of such movement, whereby the signal and motor will be operatively connected only while the signal is being moved into set position.

12. The combination in a signaling device of a signal, a motor for moving the signal into set position, connections between the motor and the signal containing two latches adapted to engage with or be disconnected from each other to connect the motor with or disconnect it from the signal, means for controlling one latch adapted to be automatically actuated by a track-circuit to cause said latch to operatively engage with the other latch when the signal is to be moved into set position and not to operatively engage with it when the signal is not to be set, and the other latch

adapted to be held against the first-mentioned latch when the signal is to be moved by the motor into set position and to be withdrawn therefrom at the close of such movement, whereby the signal and motor will be operatively connected only while the signal is being moved into set position.

13. The combination in a signaling device of a signal, a motor for moving the signal into set position, connections between the motor and the signal containing two latches adapted to engage with or be disconnected from each other to connect the motor with or disconnect it from the signal, means controlling one latch adapted to cause said latch to operatively engage with the other latch when the signal is to be moved into set position and not to operatively engage with it when the signal is not to be set, and the other latch adapted to be held against the first-mentioned latch when the signal is to be moved by the motor into set position and to be withdrawn therefrom at the close of such movement, a catch for engaging the latch connected with the signal to hold the signal in set position, and means for releasing the said latch from the catch when it is desired to permit the signal to return to its original position, whereby the signal and motor will be operatively connected only while the signal is being moved into set position and whereby the signal will be held in set position until released.

14. The combination in a signaling device of a signal, a motor for moving the signal into set position, connections between the motor and the signal containing two latches adapted to engage with or be disconnected from each other to connect the motor with or disconnect it from the signal, one latch adapted to be controlled by a train upon the track, and the other latch adapted to be held against the first-mentioned latch when the signal is to be moved by the motor into set position and to be withdrawn therefrom at the close of such movement, and a catch for engaging the latch, connected with the signal, to hold the signal in set position.

15. The combination in a signaling device of a signal, a motor for moving the signal into set position, connections between the motor and the signal containing two latches adapted to engage with or be disconnected from each other to connect the motor with or disconnect it from the signal, means for positively holding one latch against the other latch when the signal is to be moved by the motor into set position, means for positively withdrawing it from such engagement at the close of such movement, and a catch for engaging the latch connected with the signal to hold the signal in set position.

16. The combination in a signaling device of a signal, a motor for moving the signal into set position, connections between the motor and the signal containing two latches adapted to engage with or be disconnected from each other to connect the motor with or disconnect

it from the signal, one latch adapted to be held against the other latch when the signal is to be moved by the motor into set position and to be withdrawn therefrom at the close of such movement, and a catch for engaging the latch connected with the signal to hold the signal in set position, and means controlled by the train on the track to hold the latter latch in engagement with the other latch and with the catch or to disconnect it therefrom.

17. The combination in a signaling device of a signal, a motor for moving the signal into set position, connections between the motor and the signal containing two latches adapted to engage with or be disconnected from each other to connect the motor with or disconnect it from the signal, means controlling one latch adapted to cause said latch to operatively engage with the other latch when the signal is to be moved into set position and not to operatively engage with it when the signal is not to be set, and the other latch adapted to be held against the first-mentioned latch when the signal is to be moved by the motor into set position and to be withdrawn therefrom at the close of such movement, a catch for engaging the latch connected with the signal to hold the signal in set position, and means controlled by a train on the track to release said latch from the catch to permit the signal to return to its normal position.

18. The combination in a signaling device of a signal, a motor for operating it, connections between the motor and the signal consisting of a wheel having one or more lugs on its side, a movable arm concentrically mounted with the said wheel and connected with the signal, a latch carried on said arm, electrical means controlled by a train on the track for causing said latch to operatively engage with or be disengaged from a lug on said wheel, means for preventing the wheel from backward rotation and means controlled by a train on the track for energizing the motor and means for automatically deenergizing the motor when the signal has been moved to set position.

19. The combination in a signaling device of a signal, a rotary power-wheel for moving the signal into set position, an arm mounted concentrically with the power-wheel and connected with the signal, a latch and a magnet for controlling the same, both mounted upon the said arm, a projection from the power-wheel adapted to make contact with the latch as the wheel rotates, means for preventing backward rotation of the power-wheel, means controlled by a train on the track for energizing or deenergizing said magnet to cause the said latch and projection to operatively engage with or be disconnected from each other, means controlled by the train on the track for causing the power-wheel to rotate and for automatically stopping it when the signal has reached its set position.

20. The combination in a signaling device

of a signal, a motor for operating it, connections between the motor and the signal including a power-wheel adapted to be driven by the motor, a movable arm concentrically mounted with the said wheel and connected with the signal, a latch carried on said arm, a projection on the power-wheel adapted as the wheel rotates to make contact with the said latch, and means for causing said latch to operatively engage with or be disengaged from said projection, whereby motion may or may not be transmitted from the power-wheel to the signal to move it into set position or to leave it unaffected by the rotation of the power-wheel.

21. The combination in a signaling device of a signal, a motor for operating it, connections between the motor and the signal including a power-wheel adapted to be driven by the motor, a movable arm concentrically mounted with the said wheel and connected with the signal, a latch carried on said arm, a projection on the power-wheel adapted as the wheel rotates to make contact with the said latch, means controlled by a train on the track for causing said latch to operatively engage with or be disengaged from said projection, whereby motion may or may not be transmitted from the power-wheel to the signal to move it into set position or to leave it unaffected by the rotation of the power-wheel, means controlled by a train on the track for actuating the motor to move the signal to set position, and means for deenergizing the motor when the signal has been moved into set position.

22. In an electrically-controlled apparatus for converting rotary motion into rectilinear

motion to move a signal or other object into set position, the combination of a power-wheel, a rectilinearly-moving rod connected with the signal, a lever having pivotal connections with said rod and mounted concentrically with the power-wheel and adapted when connected with the power-wheel to rotate with it, means for connecting and disconnecting said lever and power-wheel and a magnet mounted upon said lever and rotatable therewith for controlling said connecting and disconnecting means.

23. In an electrically-controlled apparatus for converting rotary motion into rectilinear motion to move two signals or other objects into set positions independently of each other, the combination of a power-wheel, a rectilinearly-moving rod for each signal or other object connected therewith, a lever having pivotal connections with each rod and mounted concentrically with the power-wheel, and when connected with the latter, rotatable therewith, a clutch carried by each lever for connecting and disconnecting its lever and the power-wheel and a magnet mounted upon said lever and rotatable therewith for controlling each clutch, whereby the two signals or other objects may be moved by the power-wheel into set position independently of each other.

In testimony whereof I have signed my name to this specification in the presence of two subscribing witnesses.

CLARENCE W. COLEMAN.
